Filed May 31, 1974, Ser. No. 475,161

Term of patent 14 years

Int. Cl. D22—05

U.S. Cl. D22—27

FIG. 1 is a side elevational view of a fishing lure embodying my new design;

FIG. 2 is a front elevational view of the lure taken along line 2—2 in FIG. 1;

FIG. 3 is a rear elevational view of the lure taken along line 3—3 in FIG. 1;

FIG. 4 is a partial cross-sectional view taken along line 4—4 in FIG. 2; and

FIG. 5 is a partial cross-sectional view taken along line 5—5 in FIG. 3.

The lure is symmetrical in construction and those sides not shown are mirror images of those shown.

I claim:

The ornamental design for a fishing lure, substantially as shown and described.
